UNITED STATES PATENT OFFICE

148,938

DESIGN FOR A LUMINOUS PENDANT

John C. MacLennan, Toronto, Ontario, Canada

Application December 4, 1946, Serial No. 135,247
In Canada June 20, 1946

Term of patent 14 years

(Cl. D48—14)

To all whom it may concern:

Be it known that I, John C. MacLennan, a subject of the King of Great Britain, resident of the city of Toronto, in the Province of Ontario, Dominion of Canada, have invented a new, original, and ornamental Design for a Luminous Pendant, of which the following is a specification, reference being had to the accompanying drawing, forming part thereof.

Fig. 1 is a side elevation of the luminous pendant showing my new design.

Fig. 2 is a bottom end view thereof.

Fig. 3 is a perspective view thereof.

I claim:

The ornamental design for a luminous pendant, as shown.

JOHN C. MACLENNAN.
